UNITED STATES PATENT OFFICE.

FREDERICK A. ENGLISH, OF CHICAGO, ILLINOIS, ASSIGNOR TO BIRTMAN ELECTRIC COMPANY, OF CHICAGO, ILLINOIS, A CORPORATION OF ILLINOIS.

SUCTION-CLEANER.

1,012,195.

Specification of Letters Patent. Patented Dec. 19, 1911.

Application filed March 11, 1911. Serial No. 613,941.

To all whom it may concern:

Be it known that I, FREDERICK A. ENGLISH, a citizen of the United States, residing at Chicago, in the county of Cook and State of Illinois, have invented a new and useful Improvement in Suction-Cleaners, of which the following is a specification.

My invention relates to an improvement in the class of pneumatic cleaners in which a motor operates a fan or blower to suck through a tube dust and other foreign matter from carpets, floors, furniture and other articles or furnishings in rooms and hallways of buildings; and it relates, more particularly stated, to the construction of the suction-tube to render it adjustable for adapting its head-carrying end to be readily applied by the person handling the tube to cut-of-the-way places, such as the tops of moldings, the floors beneath beds and couches, and the like, and thus render such places conveniently accessible.

Additional features of improvement are hereinafter described.

In the accompanying drawings, Figure 1 is a broken view in side elevation of the dust-tube of my improved construction; Fig. 2 is a similar view of the same, showing one adjustment of the flexible section of the tube; Fig. 3 is a similar view of the same, showing another adjustment and demonstrating a purpose thereof; Fig. 4 is an enlarged section on line 4, Fig. 1; Fig. 5 is a broken view of the tube in longitudinal sectional elevation, showing the sight-glass feature; Fig. 6 shows the sight-glass by a plan view, and Fig. 7 is a section on line 7, Fig. 5; Fig. 8 is a broken view showing the suction-head or nozzle in rear elevation, and Fig. 9 shows the same by a face-view.

The tube 10 is formed of metal with a flexible section 12, which may be braided wire or other, preferably elastic, hose on its distal end and to which the suction-head 14 is fastened at a socket 13 thereon, the head being of the shape illustrated, or of any other suitable shape. A rod 15, which may be of metal, and hollow for lightness, is pivotally connected at one end to the under edge of the head, as shown at 16, and extends therefrom along the tube through guide-loops 17, at intervals thereon, the rearmost one of which loops carries a set-

screw 18 to bear against the rod and secure it in its retracted position.

To use my improved suction-tube it is connected at its rear end, as usual, with a dust receptacle, such as that commonly provided in the upper part of the casing of an ordinary portable suction-cleaner containing a motor and a fan or blower. With the motor in action, the user of the apparatus applies the head 14 to or moves it along the surface to be cleaned. To adapt the head to be applied to a ceiling, the flexible section 12 may be adjusted, by properly moving the rod 15 lengthwise in its guides and fastening it by the set-screw 18, to extend in line, or approximately in line, with the rod. By releasing the rod and drawing it backwardly to any desired extent, the flexible section is bent into goose-neck form to extend the head 14 at any required angle relative to the tube, thereby to adapt it to be applied by the user to the upper side of molding 19 high up on a wall 20, as indicated in Fig. 3, or to any otherwise inconveniently accessible elevated surface or object in a room, requiring to be cleaned. I prefer to form the tube with a rotatably-adjustable, rear section 21 coupled to the main section to deflect it from the straight line of the latter, whereby turning the section 21 to extend its deflected portion upwardly, as represented in Fig. 2, adapts the head with the flexible section 12 bent into the condition shown in that figure, to be inserted under a bed, couch or the like for cleaning the floor thereunder without requiring the operator to stoop for the purpose. The tube-section 21, as shown in Fig. 5, is telescopically connected at its forward end with the rear end of the main tube 10 to adapt the section to be rotated at that connection.

As a desirable position for a sight-glass device 22 I provide it, of usual or any suitable construction, on the upper side of a coupling 23 which is interposed in the tube-section 21 where it is more convenient, in the more ordinary condition of the tube 10 for use, to the observation of the operator.

The head 14 may be permanently fastened in place on the flexible tube-section 12; and since it is desirable to use, for different purposes, heads having inlet-openings of different shapes and areas, I adapt

the head 14 to have detachably fastened to it such other heads. To this end I provide jaws 24 and 25 (Fig. 9) diagonally opposite each other on the front and rear edges 5 near the ends of the face of the head to adapt such another head, fitting flatwise against it and provided with similar jaws to register with the jaws 24, 25, to be readily fastened to it, as by means of bolts 10 releasably confined in the registering jaws.

What I claim as new and desire to secure by Letters Patent is:—

1. In combination, a suction-cleaner dust-tube comprising a rigid tube, a section of 15 flexible hose on the forward end of said tube, and a suction-head connected with the advance-end of said section, and means for

bending the hose-section and securing it in different positions relative to the rigid tube, for the purpose set forth.

20

2. In combination, a suction-cleaner dust-tube comprising a rigid tube, a section of flexible hose on the forward end of said tube and a suction-head connected with the advance-end of said section, a guide-loop 25 on said tube provided with a set-screw, and a rod connected with said head and extending lengthwise of the tube through said loop, for the purpose set forth.

FREDERICK A. ENGLISH.

In presence of—

J. G. ANDERSON,
OTTILIE C. AIRSUS.
